MONOLITHIC REENFORCEMENT

Gerald G. Greulich, Cleveland Heights, Ohio, assignor to The Lock-Steel Company, Pittsburgh, Pa., a corporation of Delaware

Application May 25, 1931. Serial No. 539,651

6 Claims. (Cl. 72—109)

This invention relates to wall, floor, or ceiling construction, and more particularly to means for reenforcing and rendering burglar-proof the floors, walls and ceilings of bank vaults. In order to increase the difficulty of breaking through walls of a bank vault, it is desirable to use hardened tool resisting steel for the reenforcing material so as to require the use of a torch to cut away the metal. Where the reenforcement is fabricated by processes which include bending, crimping or expanding, it is impossible to utilize hardened tool steel throughout for such metal cannot be subjected to such operations. Furthermore, the manner of imbedding the metal in the concrete, has in many cases been unsatisfactory for it has been a comparatively easy matter to chip away the concrete and then strip large sections from the wall. Again, where the metal lacks sufficient structural strength, it has been comparatively easy to demolish the wall by an explosive force.

An object of the present invention therefore, is to provide a simple and effective reenforcement that may be made entirely of tool resisting steel and that may be interlocked so as to require the metal to be cut into sections regardless of the angle at which an attempt is made to pierce the wall. Furthermore, the present invention is directed toward a reenforcement, which enables the parts to be completely fabricated at the factory and compactly nested for shipment, and conveniently handled at the time and place of installation. An additional object of my invention is to provide a slab reenforcement, which in addition to its tool resisting characteristics is capable of increasing the resistance of the wall to demolition by explosive force and the load stresses incident to the collapse of a building by fire or otherwise.

The preferred form of carrying out my invention is shown in the drawings, wherein Fig. 1 is a horizontal section of the concrete wall embodying my reenforcing members; Fig. 2 is a vertical section taken on the line 2—2 of Fig. 1; Fig. 3 is a perspective view illustrating one of the units; Fig. 4 is a perspective view showing the interlocking relationship of the units; Fig. 5 is a horizontal section of a concrete wall embodying a modification of my invention; Fig. 6 is a vertical section taken on the line 6—6 in Fig. 5; Fig. 7 is a perspective view illustrating the cross bars removed from the end bars, and Fig. 8 is a perspective view showing the interlocking relationship of the units.

My invention is shown in Fig. 1 in connection

with a concrete wall 10, but it is to be understood that it is intended for use in connection with the reenforcement of a ceiling, or floor, as well. The reenforcement is preferably in the form of units which are adapted to be handled individually and then interlocked at the time of installation. In the preferred form, each unit comprises a pair of longitudinally extending members 11 and 12, which are interconnected by V-shaped cross or transverse members 13. The ends of the cross members may be bent as at 14, to embrace the end members and are preferably welded to the end members at the factory. In addition, the cross members may be staggered, as is shown in Fig. 3, so that the apex of one extends on one side of the plane of the longitudinal members, while the apex of the adjacent one extends on the opposite side of such plane.

The units so fabricated can be readily nested for shipment either on a gondola, or a flat car, and can be supplied in any desired length in accordance with the dimensions of the vault to be reenforced. At the place of installation, the units are placed in side by side relationship, and the cross members are interfitted and aligned. Thereupon, interlocking bars 15 are passed through the interfitting portions whereby the units are interlocked and the entire structure approximates an articulated unit of great strength. By so shaping the cross members that the longitudinal members are relatively close together and also by spacing the cross members relatively close together, it is apparent that an opening sufficient in size to admit a man cannot be made through the wall without cutting the steel into small sections, for at no point can the steel be stripped in layers extending either transversely or obliquely to the wall.

In Figs. 5 to 8, I have shown a modification of my invention wherein the staggered cross bars are replaced by diamond shaped bars 20, each of which are formed from a single bar that is bent intermediately to provide a loop 21 through which one of the end bars may be passed. The free ends of the bar 20 are then bent toward each other to provide a loop 22 through which the other end bar may be inserted. Between the loops 21 and 22, each bar is preferably bent to provide oppositely disposed V-shaped portions 23 and 24, which when interfitted provide aligned openings through which locking bars may be inserted.

The construction which I have illustrated and described provides an interlocked reenforcement which resists stresses in every direction. This is

apparent from an inspection of the drawings, wherein the end members or interlocking members are arranged in substantially parallel rows, while the cross members extend obliquely to the 5 rows and thereby offer resistance to the method of piercing a wall by means of a wedge shaped opening. A further advantage is that the entire reenforcement is interlocked so that in effect it constitutes a chain, which will add materially 10 to the structural strength of the wall and prevent buckling in case of fire or explosion. A further valuable and practical advantage is the fact that the reenforcement may be fabricated with ordinary welding equipment and that the 15 arrangement and size of the parts may be selectively controlled and varied to suit any particular specification.

I claim:

1. A reenforcement for a slab of building material, comprising a plurality of units each comprising end members and transverse members, some of the transverse members extending on one side of the plane of the end members and the remaining transverse members extending on the 25 opposite side of the plane, and all of the transverse members being rigidly connected to the end members at spaced intervals.

2. A reenforcing unit for a slab of building material, comprising a pair of substantially parallel end bars and V-shaped cross bars rigidly connecting the end bars at spaced intervals and in staggered relationship with reference to the plane of the end bars, and the cross-bars being disposed in a plane normal to the plane of the 35 end bars.

3. A reenforcement for building construction, comprising a unit having a pair of end bars and transverse bars welded thereto and in staggered relationship with reference to the plane of the end bars, the offset of the transverse members on one side of the plane being substantially equal to the offset of those on the opposite side of said plane.

4. A reenforcement for a slab of building material, comprising a unit having a pair of end bars, a plurality of cross members rigidly connected to the end bars, and being disposed in staggered relationship thereon, the cross bars being substantially similarly formed and the offset of those on one side of the plane of the end bars being substantially equal to the offset of those on the opposite side of said plane whereby all of the cross bars on each side of said plane are in alignment.

5. A reenforcing unit for a slab of building material, comprising a unit having a pair of end bars, and cross bars connected to the end bars at spaced intervals thereon, the cross bars being placed on opposite sides of the plane of the end members to form a diamond.

6. A reenforcing unit for a slab of building material, comprising a pair of end bars and spaced cross bars, each cross bar being disposed in a plane normal to the plane of the end bars, and being formed of a single strip that is bent intermediate, and looped around one of the bars, and that has the free ends engaging the other of said bars.
